(57) **CLAIM**

The ornamental design for a set of tableware for kids, as shown and described.

DESCRIPTION

FIG. 1 is a perspective view of a set of tableware for kids showing my new design;

FIG. 2 is a front elevational view of the spoon portion with the rest of the elements removed for ease of illustration;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof;

FIG. 8 is a perspective view thereof;

FIG. 9 is another perspective view thereof;

FIG. 10 is a front elevational view of the fork portion with the rest of the elements removed for ease of illustration;

FIG. 11 is a rear elevational view thereof;

FIG. 12 is a left side view thereof;

FIG. 13 is a right side view thereof;

FIG. 14 is a top plan view thereof;

FIG. 15 is a bottom plan view thereof;

FIG. 16 is a perspective view thereof;

FIG. 17 is another perspective view thereof;

FIG. 18 is a front elevational view of the plate portion with the rest of the elements removed for ease of illustration;

FIG. 19 is a rear elevational view thereof;

FIG. 20 is a left side view thereof;

FIG. 21 is a right side view thereof;

FIG. 22 is a top plan view thereof;

FIG. 23 is a bottom plan view thereof;

FIG. 24 is a perspective view thereof;

FIG. 25 is another perspective view thereof;

FIG. 26 is a front elevational view of the bowl portion with the rest of the elements removed for ease of illustration;

FIG. 27 is a rear elevational view thereof;

FIG. 28 is a left side view thereof;

FIG. 29 is a right side view thereof;

FIG. 30 is a top plan view thereof;

FIG. 31 is a bottom plan view thereof;

FIG. 32 is a perspective view thereof;

FIG. 33 is another perspective view thereof;

FIG. 34 is a front elevational view of the salt/ pepper shaker portion with the rest of the elements removed for ease of illustration;

FIG. 35 is a rear elevational view thereof;

FIG. 36 is a left side view thereof;

FIG. 37 is a right side view thereof;

FIG. 38 is a top plan view thereof;

FIG. 39 is a bottom plan view thereof;

FIG. 40 is a perspective view thereof;

FIG. 41 is another perspective view thereof;

FIG. 42 is a front elevational view of the snack container portion with the rest of the elements removed for ease of illustration;

(Continued)

FIG. 43 is a rear elevational view thereof;
FIG. 44 is a left side view thereof;
FIG. 45 is a right side view thereof;
FIG. 46 is a top plan view thereof;
FIG. 47 is a bottom plan view thereof;
FIG. 48 is a perspective view thereof;
FIG. 49 is another perspective view thereof;
FIG. 50 is a perspective exploded view of the snack container portion with the rest of the elements removed for ease of illustration; and,
FIG. 51 is another perspective exploded view thereof.
